ABSTRACT: A tobacco leaf classifier including a primary separation chamber and a secondary separation chamber, said secondary chamber receiving middlings from said first chamber and each of said chambers operating in independent air circuits.

PATENTED JUL 20 1971

3,593,851

TOBACCO LEAF CLASSIFIER

This application is a continuation of the copending application Ser. No. 760,122 filed Sept. 12, 1968, now abandoned, which itself was a continuation of Ser. No. 535,562 filed Mar. 18, 1966, now abandoned, for which all legal and equitable rights are claimed.

This invention relates to a method and apparatus for classifying tobacco leaf.

U.S. Pat. Nos. 2,941,667 and 3,034,646 disclose pneumatic tobacco leaf classifiers having as an object the separation of leaf or free lamina from stem-attached-lamina or other unwanted particles in a tobacco mixture. Both patents disclose apparatus including an air supply and a pair of separating chambers in and through which the tobacco mixture is blown. The dual chambers individually act upon only a portion of the mixture. Actually such apparatus is an outgrowth of the prior single chamber devices and was provided with a second chamber to obtain some benefit from an excess air supply.

The apparatus of both the aforementioned patents has enjoyed considerable commercial success, nevertheless they have been found to have certain serious disadvantages and defects. In each, the air chambers are interconnected creating an interference in each chamber of the air supply. Effective separation, because of this interference, is hampered. A second disadvantage arises from the fact that there is only one air supply which prevents the selection and control of varying airflows and forces for the particular lamina in each of the separate chambers.

Another disadvantage arises from the fact that, in each of the aforementioned patents the second separator was designed merely as an auxiliary and was quite small relative to the primary separating chamber. The second chamber is thus not very effective in separating leaf lamina from stems and other impurities.

It is the primary object of the present invention to provide a method and apparatus over coming the noted disadvantages of the prior art and being considerably more effective and efficient.

The concept of this invention is to provide two distinct and major separating chambers, two air supplies one for each chamber and to provide an air lock distributing means between the two chambers.

Other objects, features and concepts will appear as the description of the particular physical embodiment selected to illustrate the invention progresses. In the appended drawings;

FIG. 1 is a side elevational view of the novel tobacco classifying apparatus; and

FIG. 2 is a plan view thereof.

With reference to FIG. 1, there is seen a classifier comprising a structure generally designated S on top of which is an intake unit 10 and the end 12 of which leads from a previous separator or from a thresher or other tobacco mixture supply. The intake unit 10 is provided with a baffle 14 and an air lock rotor 16 which deposits the incoming tobacco mixture onto a winnower 18 for dispersion in the interior or primary chamber 20 of the classifier S.

The tobacco mixture is introduced into the intake unit 10 by pneumatic means located in the prior separator or tobacco mixture supply for example, augmented by suction blower 22 connected by means of duct 24 to the intake unit 10. A screen 25 is provided to prevent the tobacco mixture from entering into blower 22.

In the drawings the flow of air and the streams they follow are shown by the flow arrows.

The classifier S is connected in a closed air circuit comprising blowers 26 and 28 having their exhausting ends connected separately via ducts 30 and 32 respectively to air intake plenums 34 and 36. A screen 38 separates the plenums 36 from the primary chamber 20 of the classifier S.

The classifier S itself comprises a closed structure which has at its air entrant end, that is, within the plenums 34 and 36, air straightening baffles and at its air exiting ends a pair of duct

separating chambers 40 and 42. The tobacco mixture within primary chamber 20 is forced by the air entering through plenums 36 to separate, the lighter leaf lamina exhausting through the duct 40 while the heavier particles fall onto the 5 endless moving conveyor belt 44 traversing the bottom portion of the primary chamber 20.

The tobacco mixture on conveyor 44 is carried to an air lock rotor 46 rotating in the direction of the arrow 48 which hurls the tobacco across the width of and disperses the mixture into a secondary chamber 50 formed at the base of duct 42. Meanwhile the entrant air from plenum 34 flows beneath the conveyor 44 into the secondary chamber 50 causing the upward separation of the additional light leaf lamina from the stem or other particles. The remaining stem and lamina mixture falls into another air lock 52 and is exhausted through duct 54 into another classifier or thresher unit as desired.

The light lamina from both the primary and secondary separation chambers is exhausted via ducts 40 and 42 to a 10 combined discharge separation unit 56, (similar in construction to the intake unit 10) into or onto a collector such as a conveyor (not shown). The exhaustion of the lamina is facilitated by connection, via ducts 60 and 62, of the discharge unit 56 to the suction ends of blowers 26 and 28 respectively.

Following the above description it will be seen that the 15 present invention provides truly dual separating chambers of substantial size sufficient to separate in each light lamina from heavy stems; completely separate and independent air supplies capable of individual control airflow; (dampening devices and air control means may be used since their details are well known in the art); and an air lock between the two chambers which effectively disperses the tobacco from the primary chamber into the secondary chamber while keeping a seal between the two chambers so that no interaction between 20 the air supplies occur.

In the structure shown, the blower is made to serve both the 25 intake and the discharge ends of the separator, the complete separation of the air streams is accomplished by providing a divided air discharge unit 56 and separate fans, 26 and 28. 30 However, the two ducts 40 and 42 could carry the lamina to completely independent discharge units, the essential feature being to provide separate fans and damper controls for each air supply. If the air supplies are to be recirculated through the 35 machine, the inlet chamber to the machine must provide a partition 64 or similar means for directing the one air supply to the primary separating chamber 20 and the other air supply to the secondary chamber 50 as shown.

It is also noted that it is possible to provide more than two 40 separation chambers. In fact the number of separation chambers may be multiplied as desired, although it is believed that with more than the two provided here in increase in efficiency 45 which might be obtained is not worth the extra cost of fabrication.

Further description of the drive means, damper controls 50 motor means for the conveyor etc., are not believed necessary in view of the description of similar items in the aforementioned patents. The structure, operation, functioning and the advantages of the present classifier of the present invention and the underlying principles thereof will be fully apparent from the above description. It will be further apparent that changes may be made in the various parts without departing from the principles and spirit of the invention as defined in the 55 following claims.

60 I claim:

1. A classifier for separating lamina product in a tobacco mixture, comprising a first and second sealed separating chamber connected by an air lock rotor, each of said chambers having air entrant openings and air exit openings disposed generally parallel to each other for airflow, means for independently flowing air in a closed circuit through each of said chambers means for introducing a tobacco mixture into the first of said chambers whereby said airflow causes the separation of lamina product from said tobacco mixture, said lamina product being carried by said air flow through the exit opening

of said first chamber, means for collecting the remaining tobacco mixture and for introducing said remaining tobacco mixture into said second separation chamber through said air lock, whereby the airflow therein causes the further separation of lamina product from said remaining tobacco mixture, said lamina product being carried by said airflow through said exit opening of said second chamber, a pair of tobacco-air separators connected respectively to the exit openings of each chamber for separating the lamina for said airflow, said airflow means comprising a pair of suction blowers, the blower end of each being connected respectively to the entrant openings of said chambers, the suction ends of each being connected respectively to the tobacco-air separator of each chamber, whereby airflow and separation of tobacco within each chamber is maintained independently through said closed circuit.

2. The classifier according to claim 1 wherein the means for introducing the tobacco comprises a closed housing having a tobacco entrant opening, a tobacco exit opening and air exit opening, said tobacco entrant opening being located in the top of said housing and adjacent one side thereof, said tobacco exit opening being located opposite to said entrance, said air exit opening being located in the side of said housing opposite and in the same vertical plane as the side adjacent said tobacco entrant and exit openings, solid baffle means being adapted

to prevent transverse movement of said tobacco within said housing, air lock rotor means located at said tobacco exit opening, suction means located at said air exit to draw air from said housing whereby tobacco is caused to enter said entrant opening and to flow vertically from said entrant opening past said baffle and to exit by said air lock rotor means while said air exits oppositely therefrom.

3. The classifier according to claim 1 in which the tobacco-air separator comprises a closed housing having a tobacco and air entrant opening, a tobacco exit opening and a separate air exit opening, a tobacco and air entrant opening being located in the top of said housing and adjacent one side thereof, said tobacco exit opening being located opposite to said entrance, said air exit opening being located in the side of said housing opposite and in the same vertical plane as the side adjacent said tobacco entrant and exit openings, solid baffle means located centrally within said housing, and in a vertical plane generally perpendicular to the plane of said openings, said baffle means being adapted to prevent transverse movement of said tobacco within said housing, the suction end of the suction-blower means located at said air exit to draw air from said housing whereby tobacco is caused to enter said entrant opening past said baffle and to exit by said tobacco exit opening while air exits only through said air exit opening.
